UNITED STATES PATENT OFFICE

PAUL O. UNGER, OF SYRACUSE, NEW YORK

LOOSE LEAF BINDER

Application filed September 23, 1929. Serial No. 394,526.

This invention relates to a new and improved loose leaf binder.

Although my invention may be used with different types of loose leaf binders, it is particularly well adapted for use with that type of binder in which there is provided a pair of rear housings hingedly connected together and adapted to be moved towards and from each other so that the prongs carried by them may be placed in different relations to permit the removal or insertion of leaves or the transfer of leaves from one position in the binder to another position.

In binders of this type, there is usually provided a latch for holding the rear housings in the closed position and also it is desirable to provide a means whereby the rear housings may be releasably held in the different relative positions which they are adapted to assume.

In binders of this character, it has hitherto been necessary to release the latch and hold the same in the released position until the rear housings had been moved away from each other toward the next latching position. Such an arrangement is inconvenient in use because it necessitates the manipulation of the rear housings while at the same time, the latch is held in the unlatching position.

The main object of my invention is to provide a latch for the type of binder herein described which may be placed in the unlatched position by a single movement of a crank or other means and which will, irrespective of such crank, remain in the unlatched position until the housings have been moved to the next operative position.

Another object is to provide a latching means which will automatically return to the latched position when the housings have been moved to a new operative position.

Other objects and advantages relate to the size, shape and arrangement of parts, all as will more fully appear from the following description taken in connection with the accompanying drawings in which:

Figure 1 is a top plan view, partially broken away, of my improved binder with the housings in the closed position.

Figure 2 is a section on line 2—2 of Figure 4.

Figure 3 is a section on line 3—3 of Figure 2.

Figure 4 is a section on line 4—4 of Figure 1.

Figure 5 is a section on line 5—5 of Figure 2 with the housings in the open position.

Figure 6 is a section on line 6—6 of Figure 5.

Figure 7 is a section similar to Figure 6 and on line 7—7 of Figure 5, showing the parts in a different relative position.

Figure 8 is a section on line 8—8 of Figure 1.

Figure 9 is a section on line 9—9 of Figure 8.

For the purpose of illustrating my device and its mode of operation, I have here shown a loose leaf binder embodying certain novel features as disclosed in an application filed by John L. McMillan filed October 13, 1928, Serial No. 312,273, although it will be understood that although my invention is particularly well adapted to be used with the type of binder there disclosed, it may be used with various types of loose leaf binders in which the rear housings are adapted to be releasably held in a plurality of relative positions.

The loose leaf binder 1 here illustrated comprises a rear housing 2 and an opposed rear housing 3 hingedly connected together on their inner and lower longitudinal edges as by a piano hinge 4.

On housing 3, I provide a plurality, in this case shown as eleven, arcuate prongs 5 rigidly connected thereto.

In housing 2, I provide a plurality, in this case shown as ten, arcuate prongs 6 normally positioned in staggered relation to prongs 5. Prongs 6 are pivotally mounted in housing 2 as by clips 7, secured to the inside of the outer longitudinal wall of housing 2.

The bottom ends of prongs 6 extend inwardly towards the inner longitudinal edge of housing 2 with their ends extending vertically into engagement with slots 8 in a bar 9 which is slidably mounted in housing 2 so that the longitudinal movement of bar 9 will

cause the pivotal movement of prongs 6 in housing 2.

For the purpose of providing a convenient means for the reciprocation of bar 9, I provide on the upper surface of housing 2, a bell-crank 10 which is pivotally mounted on bar 9 as by pivot pin 11, which pivot pin 11 extends upwardly through a slot 12 in the top plate 13 of housing 2.

10 One end of bell-crank 10 is provided with a knob 14 and the other end of bell-crank 10 is formed with a U-slot in registration with a headed pin 15 fixed in top plate 13 so that if bell-crank 10 is moved about its pivot 12, 15 the end of bell-crank 10 carrying the U-slot will be held against longitudinal movement with respect to housing 2 with the result that bar 9 will be moved longitudinally of housing 2, the direction depending upon the direction of rotation of bell-crank 10.

A cam plate 16 has one end secured in housing 3 and has the other end extending into housing 2 above the upper surface of plate 9 and between opposed rolls 17 and 18 25 carried on plate 9.

The main body of cam plate 16 is approximately the same width as the distance between rolls 17 and 18 so that when the housings are in the closed position, plate 9 will be held 30 against longitudinal movement due to the fact that the main body of cam plate 16 is in position between rolls 17 and 18.

When the housings have been moved to the open position in the manner which will be 35 hereinafter described, the narrow cam surfaces carried on the end of cam plate 16 will be positioned between rolls 17 and 18 and inasmuch as the width of such narrow portion is less than the distance between rolls 17 and 40 18, longitudinal movement of plate 9 may be effected.

For the purpose of releasably securing the housings 2 and 3 in their various operative positions in relation to each other, I provide 45 a pair of spaced latches 19 and 20, each having one end pivotally mounted in housing 3 as on a rod 21 and having their other ends extending into housing 2.

Latch 19 is provided with a plurality, in 50 this case shown as three, of notches 22, 23 and 24. Notches 23 and 24 are provided with one inclined side for a purpose hereinafter to be described.

Latch 20 is provided with similar notches 55 25, 26 and 27, notches 26 and 27 being provided with one inclined side.

Latch 20 carries on the edge opposite notches 25, 26 and 27, a plurality, in this case shown as three, of spaced laterally extending 60 fingers 28, 29 and 30, each having inclined sides.

In housing 2 is slidably mounted a bar 31 provided with slots 32 and 33 through which latches 19 and 20 are adapted to move when 65 the bar 31 is in the unlocking position.

Bar 31 is normally urged towards latches 19 and 20 by a spring 34 so that it may enter the notch 22, 23 or 24 in latch 19 and the notch 25, 26 or 27 in latch 20 with which it may be in registration and when in registration with such notches, the latches 19 and 20 will be locked in position to prevent any relative movement of housings 2 and 3.

For the purpose of providing a convenient means for retracting bar 31 from registration with latches 19 and 20 to permit the relative movement of housings 2 and 3, I provide a bell-crank 35 pivotally mounted in housing 2 as by pivot pin 36.

I provide on bell-crank 35 a second bell-crank 37 pivotally mounted thereon. The outer end of bell-crank 37 is normally urged outwardly and towards plate 31 by means of a spring 38 interposed between the inner end of bell-crank 37 and one end of bell-crank 35.

The outer end of bell-crank 37 normally extends into a slot 39 in bar 31 and in contact with one end of such slot 39.

A spring 40 has one end secured to housing 2 and has the other end secured to one side of bell-crank 35 to yieldingly hold bell-crank 35 in a position where bell-crank 37 will be in registration with slot 39.

When it is desired to move bar 31 longitudinally to take it out of registration with latches 19 and 20 to permit the relative movement of housings 2 and 3, bell-crank 35 is moved about its pivot by means of a finger-hold 41 which movement of bell-crank 35 will cause the outer end of bell-crank 37 to be moved towards the end of housing 2 carrying before it bar 31.

For the purpose of temporarily holding bar 31 in the retracted position just described irrespective of bell-cranks 35 and 37, I provide in the opposite end of housing 2 and pivotally mounted therein, another bell-crank 42. Bell-crank 42 carries a laterally extending finger 43 which is normally in contact with the inner surface of bar 31 as perhaps may best be seen from Figure 6.

The end of bar 31 is provided with a shoulder 44. When bar 31 is retracted in the manner just described, the shoulder 44 will be moved beyond the end 43 of bell-crank 42 and bell-crank 42 will then move about its pivot to bring its end 43 in registration with shoulder 44 to hold bar 31 in the retracted position. Such pivotal movement of the bell-crank 42 is accomplished by means of a spring 45 interposed between bell-crank 42 and a spring support 46 secured to housing 2.

Adjacent end 43 of bell-crank 42 and in spaced relation thereto, I provide a shoulder 47. Bell-crank 42 is positioned adjacent to and in spaced relation to latch 20.

In Figure 7, I show bar 31 in the retracted position with the end 43 of bell-crank 42 in registration with the shoulder 44 on bar 31.

Between bell-crank 42 and latch 20, I pro-

vide a pivotally mounted T-shaped member 48 having an end 49 adapted to be moved into and out of registration with shoulder 47 and having another end 50 adapted to contact with fingers 28, 29 and 30 on latch 20.

For the purpose of limiting the movement of member 48 toward latch 20, I provide a stop pin 51. When bar 31 has been retracted by the manipulation of bell-crank 35 in the manner just described and the end 43 on bell-crank 42 has come into engagement with shoulder 44 on bar 31 to hold the latter in the retracted position, the housings 2 and 3 may be moved about the hinge 4.

As this movement takes place, the latch 20 will move outwardly from housing 2 and during its initial outward movement, the finger 30 will engage the end 50 on member 48 to move member 48 about its pivot and cause its end 49 to contact with shoulder 47 and this, in turn, will cause bell-crank 42 to be moved about its pivot carrying end 43 out of engagement with shoulder 44 and the bar 31 will then, by means of spring 34, be moved inwardly into contact with the edge of latch 20.

As latch 20 continues to move outwardly from housing 2, notch 26 will come into registration with bar 31 and bar 31 will, by means of spring 34, be moved into notch 26 to prevent the further outward movement of latch 20 from housing 2. If it is then desired to move housings 2 and 3 further in relation to each other, it is necessary to again manipulate bell-crank 35 to retract bar 31 from notch 26.

In Figure 7, I have shown the parts in the relative position where bar 31 has just been retracted from notch 26 and the end 43 of bell-crank 42 is in registration with shoulder 44 to hold bar 31 in the retracting position.

With the parts in this relative position, it will be seen that finger 29 is just coming into contact with end 50 on member 48 and a further outward movement of latch 20 from housing 2 will cause finger 29 to press against end 50 on member 48 to move member 48 about its pivot and to cause end 49 on member 48 to press against shoulder 47 and move bell-crank 42 about its pivot to release its end 43 from shoulder 44 so that bar 31 will be spring-pressed into engagement with slot 27 when the same comes into registration with it.

When the binder is in the open position and it is desired to close the same, it is not necessary to manipulate bell-crank 35 because of the fact that the intermediate and outer notches 23 and 24 in latch 19 and the intermediate and outer notches 26 and 27 in latch 20 have one of their sides inclined with the result that the movement of housings 2 and 3 towards each other will cause plate 31 to ride outwardly along the inclined sides of such notches and this movement will

release latches 19 and 20 and will permit the binder to close.

When the binder is in the closed position, notch 22 in latch 19 and notch 25 in latch 20 will come in registration with bar 31 to lock the parts in that position.

During the closing movement of housings 2 and 3, fingers 28, 29 and 30 will successively come into contact with end 50 of member 48, but the sides of fingers 28, 29 and 30 being inclined, they will ride over end 50 causing a slight pivotal movement of member 48 but without affecting bell-crank 42 as the movement of member 48 will be away from such bell-crank 42.

If the closing movement of housings 2 and 3 is initiated at a time when prongs 6 have been moved about their pivots in the manner heretofore described, the cam plate 16 will engage one of the rolls 17 or 18 to cause the plate 9 to be moved to the normal position as the binder is closed so that there can be no possibility of closing the binder with the prongs 6 in any but their normal position.

For the purpose of facilitating the opening movement of housings 2 and 3, I provide what is usually termed a "booster" comprising a bell-crank 52 pivotally mounted in housing 3 as by a pivot pin 53. On the lower end of bell-crank 52 and pivotally mounted thereon, I provide a link 54 adapted to move outwardly through a slot 55 in the inner side of housing 3 towards and into contact with the inner side of the housing 2.

When bar 31 has been retracted to permit the relative movement of housings 2 and 3, the upper end of bell-crank 52 is raised to cause bell-crank 52 to move about its pivot 53 and this movement will carry link 54 against housing 2 to force housings 2 and 3 about their hinge 4.

For the purpose of protecting the leaves in the binder, I provide on housing 2 a cover 56 hingedly mounted thereon and I provide on housing 3, a cover 57 hingedly mounted thereon.

For the purpose of protecting housings 2 and 3 and also for the purpose of permitting the binder to be easily moved on a desk or table, I prefer to provide in the lower outer edge of housing 2, spaced rollers 58 and 59 and I also provide in the lower outer edge of housing 3, a similar pair of spaced rollers 60 and 61.

Although I have here shown my invention as applied to a particular type of loose leaf binder, it will be understood that it is adapted to be used with different types of binders and although I have shown my invention as embodied in a particular arrangement of parts, it will be understood that the size, shape and precise arrangement of parts may be varied to a considerable extent without departing from the spirit of my invention for although I have shown and described a

specific structure and form of part as an exemplification of an embodiment of my invention, I do not desire to restrict myself to the exact size, shape or relation of parts as various changes may be made within the scope of the appended claims.

I claim:

1. A loose leaf binder comprising rear housings hingedly connected together, a cover hinged to each housing, sets of prongs carried on each housing, a latch secured to one housing and extending into the other housing, means in the latter housing for releasably engaging the latch, means for moving such engaging means out of engagement with the latch, means automatically engaging such latch-engaging means when the same has been moved to the disengaged position to hold it in such position, and means actuated by the movement of the latch for moving the last-named means out of engagement with the latch-engaging means.
2. A loose leaf binder comprising rear housings hingedly connected together, a cover hinged to each housing, sets of prongs carried on the housings, a latch secured to one housing and extending into the other housing, a bar slidably mounted in the last-named housing and adapted to engage a notch in the latch, means for retracting the bar from the notch, means automatically engaging the bar when the same has been moved to the retracted position to hold it in such position, and means actuated by the movement of the latch for moving the last-named means out of engagement with the bar.
3. A loose leaf binder comprising rear housings hingedly connected together, a cover hinged to each housing, sets of prongs carried on the housings, a latch secured to one housing and extending into the other housing, a bar slidably mounted in the last-named housing and adapted to engage a notch in the latch, means for retracting the bar from the notch, means automatically engaging the bar when the same has been moved to the retracted position to hold it in such position, and means actuated by the movement of the latch for moving the last-named means out of engagement with the bar, such means including a pivoted member adapted to be moved by the latch into engagement with the automatic means.
4. A loose leaf binder comprising opposed rear housings hingedly connected together, a cover hingedly connected to each housing, sets of prongs carried by the housings, a latch secured to one housing and extending into the other housing, means in the latter housing for releasably engaging the latch, means for retracting the latch-engaging means from the latch, a bell-crank pivotally mounted in the last-named housing and spring-pressed towards the latch-engaging means, a shoulder on the latch-engaging means adapted to register with one arm of the bell-crank when the latch-engaging means is in the disengaged position, and means actuated by the movement of the latch to pivot the bell-crank to move the same out of engagement with the latch-engaging means.

5. A loose leaf binder comprising opposed rear housings hingedly connected together, a cover hingedly connected to each housing, sets of prongs carried by the housings, a latch secured to one housing and extending into the other housing, means in the latter housing for releasably engaging the latch, means for retracting the latch-engaging means from the latch, a bell-crank pivotally mounted in the last-named housing and spring-pressed towards the latch-engaging means, a shoulder on the latch-engaging means adapted to register with one arm of the bell-crank when the latch-engaging means is in the disengaged position, and means actuated by the movement of the latch to pivot the bell-crank to move the same out of engagement with the latch-engaging means.

6. A loose leaf binder comprising opposed rear housings hingedly connected together, a cover hingedly connected to each housing, sets of prongs carried by the housings, a latch secured to one housing and extending into the other housing, a bar slidably mounted in the last-named housing and adapted to engage the latch, means for retracting the bar from engagement with the latch, a bell-crank pivotally mounted in the last-named housing and spring-pressed towards the bar, a shoulder on the bar adapted to engage the bell-crank when the bar is moved to the disengaged position, and means actuated by the movement of the latch for moving the bell-crank about its pivot and out of engagement with the shoulder on the bar.

7. A loose leaf binder comprising opposed rear housings hingedly connected together, a cover hingedly connected to each housing, sets of prongs carried by the housings, a latch secured to one housing and extending into the other housing, a bar slidably mounted in the last-named housing and adapted to engage the latch, means for retracting the bar from engagement with the latch, a bell-crank pivotally mounted in the last-named housing and spring-pressed towards the bar, a shoulder on the bar adapted to engage the bell-crank when the bar is moved to the disengaged position, and means actuated by the movement of the latch for moving the bell-crank about its pivot and out of engagement with the shoulder on the bar.

8. A loose leaf binder comprising rear housings hingedly connected together, a

cover hinged to each housing, a set of prongs carried on each housing, a latch secured to one housing and extending into the other housing, means in the latter housing for releasably engaging the latch, means for moving such engaging means out of engagement with the latch, means automatically engaging such latch-engaging means when the same has been moved to the disengaged position to hold it in such position, means actuated by the movement of the latch for moving the last-named means out of engagement with the latch-engaging means, and means for moving the latch-engaging means to the engaging position.

9. A loose leaf binder comprising rear housings hingedly connected together, a cover hinged to each housing, sets of prongs carried on the housings, a latch secured to one housing and extending into the other housing, a bar slidably mounted in the last-named housing and adapted to engage a notch in the latch, means for retracting the bar from the notch, means automatically engaging the bar when the same has been moved to the retracted position to hold it in such position, means actuated by the movement of the latch for moving the last-named means out of engagement with the bar, and means for moving the bar into engagement with a notch.

10. A loose leaf binder comprising rear housings hingedly connected together, a cover hinged to each housing, sets of prongs carried on the housings, a latch secured to one housing and extending into the other housing, a bar slidably mounted in the last-named housing and adapted to engage a notch in the latch, means for retracting the bar from the notch, means automatically engaging the bar when the same has been moved to the retracted position to hold it in such position, means actuated by the movement of the latch for moving the last-named means out of engagement with the bar, such means including a pivoted member adapted to be moved by the latch into engagement with the automatic means, and means for moving the bar into engagement with a notch.

11. A loose leaf binder comprising opposed rear housings hingedly connected together, a cover hingedly connected to each housing, sets of prongs carried by the housings, a latch secured to one housing and extending into the other housing, means in the latter housing for releasably engaging the latch, means for retracting the latch-engaging means from the latch, a bell-crank pivotally mounted in the last-named housing and spring-pressed towards the latch-engaging means, a shoulder on the latch-engaging means adapted to register with an arm of the bell-crank when the latch-engaging means is in the disengaged position, means actuated by the movement of the latch to

pivot the bell-crank to move the same out of engagement with the latch-engaging means, and means for moving the latch-engaging means to the engaging position.

12. A loose leaf binder comprising opposed rear housings hingedly connected together, a cover hingedly connected to each housing, sets of prongs carried by the housings, a latch secured to one housing and extending into the other housing, means in the latter housing for releasably engaging the latch, means for retracting the latch-engaging means from the latch, a bell-crank pivotally mounted in the last-named housing and spring-pressed towards the latch-engaging means, a shoulder on the latch-engaging means adapted to register with one arm of the bell-crank when the latch-engaging means is in the disengaged position, means actuated by the movement of the latch to pivot the bell-crank to move the same out of engagement with the latch-engaging means, such means including a pivoted member adapted to be moved into contact with one arm of the bell-crank, and means for moving the latch-engaging means to the engaging position.

13. A loose leaf binder comprising opposed housings hingedly connected together, a cover hingedly connected to each housing, sets of prongs carried on the housings, a latch having a plurality of notches secured to one housing and extending into the other housing, a bar slidably mounted in the last-named housing and adapted to engage the latch, means for retracting the bar from engagement with the latch, a bell-crank pivotally mounted in the last named housing and spring-pressed towards the bar, a shoulder on the bar adapted to engage the bell-crank when the bar is moved to the disengaged position, means actuated by the movement of the latch for moving the bell-crank about its pivot and out of engagement with the shoulder on the bar, and means for moving the bar into engagement with a notch in the latch.

14. A loose leaf binder comprising opposed housings hingedly connected together, a cover hingedly connected to each housing, sets of prongs carried on the housings, a latch having a plurality of notches secured to one housing and extending into the other housing, a bar slidably mounted in the last-named housing and adapted to engage the latch, means for retracting the bar from engagement with the latch, a bell-crank pivotally mounted in the last named housing and spring-pressed towards the bar, a shoulder on the bar adapted to engage the bell-crank when the bar is moved to the disengaged position, means actuated by the movement of the latch for moving the bell-crank about its pivot and out of engagement with the shoulder on the bar, such means including a pivoted member adapted to be moved into

- contact with one arm of the bell-crank to move the latter about its pivot, and means for moving the bar into engagement with a notch in the latch.
15. A loose leaf binder comprising opposed rear housings hingedly connected together, a cover hinged to each housing, sets of prongs carried on the housings, a latch having one end secured to a housing and the other extending into the other housing, means in the last-named housing for engaging the latch, means for moving the latch-engaging means out of engagement with the latch, means for retaining the latch-engaging means in the disengaged position, and means actuated by the movement of the latch for releasing the retaining means from the latch-engaging means.
16. A loose leaf binder comprising opposed rear housings hingedly connected together, a cover hinged to each housing, sets of prongs carried on the housings, a latch having one end secured to a housing and the other extending into the other housing, means in the last-named housing for engaging the latch, means for moving the latch-engaging means out of engagement with the latch, means for retaining the latch-engaging means in the disengaged position, means actuated by the movement of the latch for releasing the retaining means from the latch-engaging means, and means for moving the latch-engaging means to the engaging position.
17. A loose leaf binder comprising opposed rear housings hingedly connected together, a cover hinged to each housing, sets of prongs carried by the housings, a latch having one end secured to one housing and the other end extending into the other housing, means in the last-named housing for engaging the latch, means for moving the latch-engaging means out of engagement with the latch to permit the relative movement of the housings about the axis of their hinge, means for retaining the latch-engaging means in the disengaged position, and means actuated by the movement of the housings for releasing the retaining means from the latch-engaging means.
18. A loose leaf binder comprising opposed rear housings hingedly connected together, a cover hinged to each housing, sets of prongs carried by the housings, a latch having one end secured to one housing and the other end extending into the other housing, means in the last-named housing for engaging the latch, means for moving the latch-engaging means out of engagement with the latch to permit the relative movement of the housings about the axis of their hinge, means for retaining the latch-engaging means in the disengaged position, means actuated by the movement of the housings for releasing the retaining means from the latch-engaging means.
- means, and means for moving the latch-engaging means to the engaging position.
19. A loose leaf binder comprising rear housings hingedly connected together, a cover secured to each housing, sets of prongs carried on each housing, a latch for holding the housings in a selected one of a plurality of relative positions secured to one of the housings, means on the other housing for releasably engaging the latch, means for moving such engaging means out of engagement with the latch, means automatically engaging such latch-engaging means when the same is moved to the disengaged position to hold it in such position, and means actuated by the movement of the latch for moving the last-named means out of engagement with the latch-engaging means.
20. A loose leaf binder comprising rear housings hingedly connected together, a cover secured to each housing, sets of prongs carried on each housing, a latch for holding the housings in a selected one of a plurality of relative positions secured to one of the housings, means on the other housing for releasably engaging the latch in each of said positions, means for moving such engaging means out of engagement with the latch, and means automatically engaging such latch-engaging means when the same is moved to the disengaged position to hold it in such position.
21. A loose leaf binder comprising opposed back members connected together for relative movement, a latch secured to one back member, means on the other back member releasably engaging the latch, means for disengaging the last-mentioned means, automatic means for holding the latch engaging means in the disengaged position, and means actuated by the relative movement of the back members for moving the automatic means from the holding position.
22. A loose leaf binder comprising opposed housings connected together for relative movement, a set of prongs carried on each housing, a latch secured to one housing and adapted to hold the housings in a selected one of a plurality of relative positions, means on the other housing for releasably engaging the latch in each of said positions, means for releasing said latch engaging means, automatic means for holding said latch engaging means in the releasing position, and means actuated by the relative movement of the housings for moving the automatic means from the holding position.
23. In a loose leaf binder, a pair of back members, a connection between said back members permitting relative movement of the members, a latch on one back member, means on the other member adapted to engage the latch, manually operated means for moving the latch-engaging means to latch-releasing position, additional means for

maintaining the latch-engaging means in latch-releasing position, and means actuated by the relative movement of said back members for releasing said additional means.

5 24. A loose leaf binder comprising back members connected for relative movement, a cover hinged to each back member, a set of prongs carried on each back member, a latch secured to one back member, a bar slidably mounted on the other back member and adapted to engage the latch, means for moving the bar out of engagement with the latch, means automatically engaging the bar when the same has been moved out of engagement with the latch to hold it in such disengaged position, and means actuated by the relative movement of the back member for moving the last-named means out of engagement with the bar, such means including
10 20 a pivoted member adapted to be moved into engagement with the automatic means.

In witness whereof I have hereunto set my hand this 19th day of September, 1929.

PAUL C. UNGER.
